UNITED STATES PATENT OFFICE.

DONALD NOBLE, OF BRIDGEPORT, CONNECTICUT, ASSIGNEE TO THE SINGER MANUFACTURING COMPANY, A CORPORATION OF NEW JERSEY.

UNIVERSAL FEEDING MECHANISM FOR SEWING-MACHINES.

1,049,593.

Specification of Letters Patent.

Patented Jan. 7, 1913.

Original application filed November 11, 1907, Serial No. 401,644. Divided and this application filed February 11, 1911. Serial No. 607,892.

To all whom it may concern:

Be it known that I, DONALD NOBLE, a subject of the King of Great Britain, residing at Bridgeport, in the county of Fairfield and State of Connecticut, have invented certain new and useful Improvements in Universal Feeding Mechanism for Sewing-Machines, of which the following is a specification, reference being had therein to the accompanying drawings.

This invention relates to improvements in feeding mechanisms for sewing machines wherein the direction of the feed of the fabric is manually controlled through a suitable hand-crank mounted convenient of manipulation, and important to the objects attained is the providing of improved means for preventing such manual control except when the feeding mechanism is being actuated to feed the fabric, and to locate said hand-crank more convenient of manipulation.

In the earlier forms of construction of sewing machines of the character referred to above, it has been the common practice to mount the hand-crank either in a plane corresponding with or transverse to the plane of the feed of the material, both methods of which compel the operator to sit at the machine in an unnatural position, which, when long continued, becomes exceedingly tiresome, as will be readily understood by taking a position at a sewing machine convenient to its operation and giving to the hand the necessary movements to turn the crank handle, located below the bed-plate, in either a horizontal or vertical plane. To make more convenient such manual manipulation of the hand-crank, the latter is herein mounted to rotate in a plane oblique to that common to the earlier forms of construction, thus positioning the hand-crank more convenient of hand manipulation and permitting the operator to sit at the machine in a more upright and less tiresome position.

For a more convenient understanding of the present invention it is herein shown and described in connection with the crank-hem-stitch embroidering machine represented by the United States pending application Ser. No. 401,644, filed November 11, 1907, of which this is a division, and as the present invention is not limited in its application to the specific construction of stitch-forming

and cloth-feeding mechanisms represented by the pending application above referred to, only such details in construction, of the last-mentioned mechanisms, will be referred to as are deemed necessary to properly define the invention.

In the accompanying drawings illustrating the invention, in the several figures of which like parts are similarly designated, Figure 1 is a view in front side elevation of a universal feed sewing machine embodying the improved mechanism, the bed-plate and arm-standard being shown in section. Fig. 2 is a rear side elevation partially in section to better illustrate the mechanism for controlling the feed of the material. Fig. 3 is a view in perspective of the mechanism located in and carried by the rotary cylinder mounted in the free end of the bracket-arm. Fig. 4 is a vertical central section of the rotary cylinder referred to in Fig. 3. Fig. 5 is a detail view of the clutch mechanism for controlling the time at which the direction of the feed movements may be changed. Fig. 6 is a rear side elevation partially broken away to better illustrate the means employed for holding the feeding mechanism against manual manipulation except at a given time, the parts located above the bracket-arm and the stop-motion elements located at the rear of said bracket-arm being omitted. Fig. 7 is a sectional elevation on the line C D Fig. 2. Fig. 8 is a view in central cross section of the cam-disk located at the rear side of the bracket-arm.

1 is the bed-plate of the sewing machine, upon which is mounted the bracket-arm constructed with the standard 2 and laterally extending member 3, and 4 the crank-shaft journaled in bearings 5 and 6 secured in the arm standard 2.

7 is the needle-bar crank connection, connected at one end with the crank 8 and at its opposite end with the needle-bar actuating lever 9, said lever being secured on a fulcrum-pin 10 journaled in suitable bearings 11 formed in the bracket 11, which latter is suitably secured to the member 3 of the bracket-arm, the forward end of said needle-bar actuating lever being operatively connected, through a suitable connection as 12, 13 with the upper end of the hollow needle-bar 13. The needle-bar 13 is mounted to move vertically in suitable bearings formed in the

swinging frame 14, which latter, at its upper end, is suitably pivoted to the inner upper end of the rotating cylinder 15, the lower end of said needle-bar being provided with 5 needle-clamps 16 and 17 equipped with the ordinary eye-pointed needles 18 and 19, respectively.

20 is the looper-actuating crank connection, connected at one end with the crank 21 10 and at its opposite end with the looper-actuating lever 22 mounted to oscillate in a bracket 23 suitably secured to the under side of the bed-plate, the forward end of the lever 22 being operatively connected with 15 the loop-taker driving ring 24, whose oppositely arranged vertical movements gives to the loop-takers 25 and 26 their stitch-forming movements.

To the under side of the bed-plate is suitably secured a bracket 27 into which is rotatably mounted a standard 28 carrying a toothed disk 29, into which latter is rotatably secured the lower end of the loop-taker carriers 30 and 31, their upper ends 25 being journaled in a two-armed bracket 32 carried by said standard, said bracket having suitably secured to it a throat-plate 33 provided with a sliding needle-plate 34, the plate 33 being journaled in the cloth-plate 31 in a manner to form the upper fulcrum of the standard 28, thus permitting the loop-takers to revolve about the axis of said standard and to be independently oscillated upon their own axis.

35 From the foregoing it will be understood that through the connections pointed out the rotation of the crank 8 transmits vertical movements to the needle-bar and that the crank 21 transmits oscillatory movements to 40 the loop-taker.

36 represents a hand-crank shaft, the upper end of which is mounted in a bearing 37 formed in a bracket 38 later to be referred to, its lower end being mounted in a 45 bearing 39 formed in a bracket 40 secured to a lug 41 forming a part of the bed-plate, the lower end of the crank-shaft 36 being provided with a hand-crank consisting of an arm 42 and crank-handle 43, the bearings 37 and 39 being arranged to position the hand-crank shaft oblique to the plane of the upper surface of the cloth-plate, thus giving to the crank-handle rotary movements in a like oblique plane.

55 Upon the upper end of the crank-shaft 36 is secured a beveled gear 46 which meshes with a like gear 47 secured on a horizontal shaft 48, said shaft being mounted in suitable bearings formed in the member 3 of the bracket-arm. The forward end of the shaft 48 is provided with a second gear 49 which meshes with a like gear 50 carried by an upright shaft 51 which, in turn, is mounted in vertically arranged bearings 52 and 53 forming a part of said member 3, and to

the upper end of the shaft 51 is secured a toothed disk 54 which meshes with a like disk 55 secured to the upper end of the rotary cylinder 15.

Near the lower end of the hand-crank 70 shaft 36 is secured a bevel-gear 56 which meshes with a like gear 57 mounted on a second horizontal shaft 58, which latter is mounted to rotate in suitable bearings located at the under side of the bed-plate. To 75 the forward end of the shaft 58 is secured a gear 59 which coacts with a like gear 60 carried by the upright shaft 61 mounted at its lower end in a bearing formed in the bracket 27, and at its upper end in a bracket 62 secured by suitable screws (not shown), to the under side of the bed-plate, the lower end of said upright shaft being provided with a toothed disk 63 which meshes with the toothed disk 29 carried by the standard 80 28, thus completing the train of mechanism between the crank-handle 43 and the loop-takers 25 and 26, and said crank-handle and the cylinder 15, for actuating said loop-takers and cylinder and parts carried by 90 said cylinder synchronously and about a common axis.

That the needle-threads may follow the rotation of the cylinder and the needles carried by said cylinder, there is mounted upon the bracket-arm a bracket 64, the upper end of which comprises a circular portion 65 into which is journaled the hub 66 of the toothed disk 67, and to the upper side of said hub is secured by suitable screws, (not shown), 95 a disk 68 carrying the elements for furnishing and directing the sewing threads to the hollow needle-bar 13. To effect the rotation of the toothed disk 67 there is provided an upright shaft 69 carrying at its upper 100 end the toothed disk 70 and at its opposite end the toothed disk 71, said shaft 69 being journaled at its upper end in the bracket 64 and at its lower end in the element 3 of the bracket-arm, the toothed disk 70 meshing with the toothed disk 67 and the toothed disk 71 with the toothed disk 55, thus transmitting to the toothed disk 67 and parts carried by it, the necessary rotary movements.

115 The usual needle threads are passed from the supply through the respective tensions 72 72, thread-loopers 73 73, central thread-guide 74, thread opening (not shown), formed in the free end of the take-up lever 75 and through the eye 76 formed in the bracket 77 secured by screw 78 to the circular portion 65 of the bracket 64, followed by passing said threads down through the hollow needle-bar and out through suitable 120 thread-openings (not shown), to the thread-eyes of the respective needles 18 and 19. The loop-takers are provided with the usual bobbins and thread, (not shown), which latter concatenates with the needle-threads to 130

form stitches in the usual manner. The take-up lever 75 is secured to the upper end of the vertically arranged rock-shaft 79 journaled in a suitable bearing formed in the bracket 11 and actuated from a suitable cam-groove formed in the periphery of a cam later to be referred to.

80 represents a bevel-gear carried by the crank-shaft 4, said gear meshing with a bevel-gear 81 secured to the inner face of a cam-disk 82 formed integral with a hollow cam-shaft 83, the latter mounted to turn on a short shaft 84 secured by screw 85 to a bearing 86 formed integral with the member 3 of the bracket-arm. The gears 80 and 81 are of the ratio of three to one, thus effecting one rotation of the gear 81 to three complete actuations of the stitch-forming mechanism. 87 is a second cam-disk carried by the hollow shaft 83 and provided at its periphery with a cam-groove 83' which, through the take-up arm 87' and roller 87", transmits motion to the take-up lever 75, and at one side provided with a cam portion

88, which latter coacts with the free end of the oscillating bellcrank-lever 89 mounted on a shaft 90 journaled in suitable bearings formed in the member 3. One end of the lever 89 is provided with a forked projection 91 which embraces a slide-block 92, shown only in dotted lines Fig. 6, pivoted on a stud-screw 93 secured in the bracket-collar 94, said bracket-collar being secured by pinch-screw 95 to the upper end of the cloth-presser carrying bar 96. The upper portion of the bar 96 is reduced in diameter to move vertically in the depending shaft 97, which shaft is secured by a screw 98 in a hanger 99 projecting downwardly from the bracket-arm. Interposed between the shoulder formed on the bar 96 and the shoulder formed in the shaft 97 is a spring 100 which normally acts to hold the cloth-presser 101 down on the material.

45 From the foregoing it will be understood that the cam portion 88, through the connections pointed out, lifts the cloth-presser 101 in opposition to the resiliency of the spring 100, once during the formation of three lock stitches, or at the completion of each embroidery stitch.

As the piercer 102 comprises an element which may or may not be used in connection with the seam formation, dependent upon the character of the product required, it is believed that its actuating and controlling elements will be sufficiently referred to in connection with the later description of other elements more or less closely related thereto.

103 represents the step or feeding foot operated through suitable connections from a cam-groove 104 formed in the cam-disk 105 (see Fig. 1) but as it is well understood

5 ing machines are equipped with an upper feed, as in the present construction, while others are equipped with an under or fore-motion feed, as in the construction represented by United States Patent to Kohlbrenner, No. 858,724, of July 2, 1907, and as the present invention is applicable to either, it is deemed sufficient to briefly refer to the elements connecting said cam with said feeding foot.

106 represents a two-part lever secured together upon a rock-shaft 107, journaled in the free end of the bracket-arm, to move synchronously together, one end of said lever being provided with a suitable roller 80 which tracks the cam-groove 104, the opposite end of said lever being provided with a suitable roller which cooperates with the groove 108 formed in the feed-ring 109. The cam-groove 104, through the connections last pointed out, acts to move said feed-ring vertically in opposite directions once during the formation of each embroidery stitch.

110 and 111 represent the arms of a two-armed operating lever joined together at the lower ends and provided with a lug 112, the respective arms being pivoted, as at 113, on suitable lugs (not shown), forming a part of the respective brackets 44 and 45, 95 which latter are permanently secured, by suitable screws (not shown) to the inner wall of the cylinder 15. The arms 110 and 111 are provided at their upper ends with angular portions 114 and 115 which pass 100 through suitable openings formed in said cylinder and coact with the feed-ring 109. The lug 112 extends downwardly into an opening in the feeder-head 116, which latter forms a part of the swinging frame 14, 105 said lug coacting with the inner end of an adjusting screw 117 held against accidental movement by a nut 118.

From the foregoing it will be understood that when the feed-ring is moved upward 110 its action upon the angular portion 114 and 115, of the two-armed lever, causes the lug 112 to oscillate the frame 14 and parts carried by it, said frame being returned to its normal position by a spring 119, shown in 115 dotted lines only, Fig. 3, which, at one end rests in a suitable depression formed at the inner side of the bracket 120, the latter secured to the feeder-head 116 by the screw 121, the opposite end of said spring resting 120 in a suitable depression formed in the outer wall of the short cylinder 134. The piercer and feeding foot are both carried by the bar 122 which passes through a suitable opening 123 formed in the feeder-head and into 125 an opening 124 formed in the upper end of the swinging frame 14, and has secured to it by screw 125 a bracket 126 which is operatively connected, through lugs 126' and 126", with the ring 127 mounted to move 130

vertically on the cylinder 15, said ring being actuated, through suitable connections, including the two-part lever 128 by a suitable cam-groove formed on the inner side of 5 the cam-disk 87 to move the piercer and feeding foot away from the material once for each complete actuation of the needle-bar.

The cylinder 15 is mounted in the forward 10 end of the bracket-arm in suitable bearings consisting of the half bearings 129 and 130 formed in the bracket-arm, and the half bearings formed in the caps 131 and 132, which latter are secured by suitable screws

15 as 133, the cylinder being held against vertical movement by the toothed disk 55 and the short cylinder 134 secured by suitable screws (not shown) to the lower end of the cylinder 15. On the inner side of the 20 cam-disk 105 is formed a suitable cam-groove, which, through the connections now to be described, control the lateral movements of the needles.

135 represents a two-part rock-lever 25 mounted on the rock-shaft 90 and carrying at one end a suitable roller which tracks in said cam-groove, and at its outer end is operatively connected with a needle-actuating ring 136 mounted upon the cylinder 15. The 30 ring 136 has secured to its inner wall a suitable bracket which passes through a suitable opening in the cylinder 15, which bracket is provided with a suitable lug which enters the opening 137 formed in the needle cam-shaft 138. The shaft 138 is mounted 35 at its upper end in a bearing 139 carried by the swinging frame 14, its lower end entering a bearing 140 formed in the feeder-head 116. It has not been deemed necessary 40 to illustrate the bracket connecting the ring 136 with the cam-shaft 138 as its application is evident from the nature of the construction.

141 and 142 represent the needle-vibrating 45 rock-levers pivoted on complementary studs-screws 143 threaded into suitable lugs formed on the feeder-head 116, the upper ends of the respective levers being provided with rollers and carrying at their opposite 50 ends the respective studs 144 and 145. Upon the stud 144 is mounted a rocking guide-block 146 and upon the stud 145 is mounted a like block 147, said blocks being provided with complementary openings through which 55 pass the respective slide-rods 148 and 149, the lower end of the rod 148 being secured in the needle-clamp 16 and the rod 149 in the clamp 17.

150 and 151 represent inclines formed on 60 the needle cam-shaft 138, said inclines terminating in the respective straight surfaces 152 and 153 and coacting with the respective rollers through the connections described, to rock the needles outwardly in opposition to 65 the resiliency of the spring 154, thus giving

to the needles the necessary oscillatory movements to form the embroidery stitch.

To guard against the operator interfering with the feed of the material except at such time as it is being advanced under the 70 needle, the cam-disk 105 is provided with a cam section 155 and the cam-disk 87 with a complementary cam section 155', said cam sections coacting with the respective rollers 156 and 157 carried by the respective brake-levers 158 and 159, which latter are pivoted on the respective screws 160 and 161 threaded into the bracket 38.

The bracket 38 is provided with a short shaft 162 which enters a bearing 163 formed 80 in the standard 2, thus permitting said bracket to take its proper angle with respect to the shaft 36.

165 and 166 represent wedge-shaped brake-shoes provided with complementary recesses 85 167, one only of which is shown, in which are threaded the inner ends of complementary screws 168 which latter are threaded through the respective levers 158 and 159, said screws being held against accidental 90 movement by suitable jam-nuts.

169 represents the brake-pulley secured on the shaft 36 and provided with a V-shaped groove 170 corresponding in shape to the acting surfaces of the brake-shoes 165 and 95 166.

171 represents a spring, one end of which is secured to the lever 158, its opposite end being attached to the lever 159, thus acting to resiliently hold the brake-shoes into the 100 groove 170 in opposition to the action of the cam-sections 155 and its complementary cam-section carried by the cam-disk 87. From the foregoing it will be understood that when the cam-sections last above mentioned, act on the respective rollers 156 and 157, which occurs during the feeding of the material, the levers 158 and 159 are moved to release the brake-shoes from contact with the groove 170 formed in the pulley 169. 105

Owing to the stop-motion mechanism forming a part of the original application it has been included in the present figures, but as it has no bearing on the present invention, such elements as might interfere 115 with a proper understanding of the stitch-forming, cloth-feeding and feed-controlling mechanisms are designated by the numeral 175.

In sewing machines of the character hereinbefore described it will be readily seen that the time allowed for manually rotating the needles is limited to the time that they are out of the fabric, which, even when the machine is operated at comparatively slow 120 speed, is extremely small and any construction which benefits this condition of manual control permits of a proportionate increase in speed, which latter is one of the chief objects of the present invention in providing 130

a brake device in which release and control is effected through the smallest possible movement of the brake shoe or shoes. The employment of a plurality of brake-shoes, as herein shown and described, while desirable is not essential as a single brake-shoe, would meet the functional requirements of the invention.

Having thus set forth the nature of the invention, what I claim herein is:—

1. In a sewing machine, the combination with stitch-forming mechanism and universal feeding mechanism, and means for changing the direction of operation of the feeding mechanism, of normally acting means for applying a yielding resistance to the action of the feed-direction-changing means, and means automatically operated after the production of each group or succession of stitches of predetermined number to interrupt said yielding resistance.

2. In a sewing machine, the combination with stitch-forming mechanism and universal feeding mechanism, and means, including a rotary shaft, for changing the direction of operation of the feeding mechanism, of a friction wheel mounted upon said rotary shaft; a brake-shoe in normal operative engagement with said friction wheel, and means automatically operated after the production of each group or succession of stitches of predetermined number to interrupt the operative relation of the brake-shoe with said friction-wheel.

3. In a sewing machine, the combination with stitch-forming mechanism and universal feeding mechanism, and means, including a rotary shaft and manually operated turning means therefor, for changing the direction of operation of the feeding mechanism, of a friction-wheel mounted upon said rotary shaft, a brake-shoe in normal operative engagement with said friction-wheel, and means automatically operated for the production of each group or succession of stitches of predetermined number to interrupt the operative relation of the brake-shoe with said friction-wheel.

4. In a sewing machine, the combination with stitch-forming mechanism and universal feeding mechanism, and means including a rotary member and manually actuated turning means therefor whereby the direction of operation of the feeding mechanism may be changed, of a brake-wheel carried by said rotary member, brake-shoes upon opposite sides of said brake-wheel, vibratory levers by which said brake-shoes are carried, a spring for drawing said levers together, and means acting periodically to separate said levers for relieving the pressure of the brake-shoes upon said brake-wheel.

5. In a sewing machine, the combination with over-sewing-stitch-forming mecha-

nism including a laterally jogging needle, feeding mechanism, and manually actuated turning means for said stitch-forming and feeding mechanisms, of a cam member from which the needle-jogging movements are derived, a brake-wheel mounted upon an operative member of said turning means, a brake-shoe in normal operative relation with said brake-wheel, and an operative connection between said cam-member and the brake-shoe whereby the operative relation of the same with the brake-wheel is periodically interrupted.

6. In a sewing machine, the combination of a bed-plate provided with a cloth-plate and upon which is mounted the bracket-arm, a rotary stitch-forming and feeding mechanism and a feed-direction-changing mechanism operatively connected with the former mechanism, said feed-direction-changing mechanism including a hand crank located below said bed-plate at the side nearest the operator and having rotary movements in an effective plane substantially oblique to the plane of the upper surface of said cloth-plate.

7. In a sewing machine, the combination of a bed-plate provided with a cloth-plate and upon which is mounted the bracket-arm, a rotary stitch-forming and feeding mechanism and a feed-direction-changing mechanism operatively connected with the former mechanism, said feed-direction-changing mechanism including a hand crank located below said bed-plate at the side nearest the operator and having rotary movements in an effective plane substantially oblique to the plane of the upper surface of said cloth-plate, the cycle of movement of said hand crank being partially under and partially out from under said bed-plate.

8. In a sewing machine, the combination of rotary stitch-forming and feeding mechanisms and a feed-direction-changing mechanism operatively connected with the former mechanisms, said feed-direction-changing mechanism including a hand-crank shaft mounted to rotate in bearings arranged oblique to the axis of rotation of said stitch-forming and feeding mechanisms, the upper of said bearings being pivotally mounted in a part stationary with respect to the actuating mechanism of the sewing machine.

9. In a sewing machine, the combination of rotary stitch-forming and feeding mechanisms and a feed-direction-changing mechanism operatively connected with the former mechanisms, said feed-direction-changing mechanism including a hand-crank shaft mounted to rotate in bearings arranged oblique to the axis of rotation of said stitch-forming and feeding mechanisms, the upper of said bearings being pivotally mounted in the bracket-arm of the sewing machine.

10. In a sewing machine, the combination

of a rotary stitch-forming mechanism, a rotary feeding mechanism operatively connected with the latter, a feed-direction-changing mechanism operatively connected with the former mechanisms, said feed-direction-changing mechanism including a hand-crank shaft mounted to rotate on an axis oblique to the axis of rotation of said stitch-forming and feeding mechanisms, means normally acting to apply a resistance to the action of the feed-direction-changing mechanism, and means automatically operated, after the production of each group or succession of stitches of predetermined number, to interrupt the normal action of said resistance means.

11. In a sewing machine, the combination of a rotary stitch-forming mechanism, a rotary feeding mechanism operatively connected with the latter, a feed-direction-changing mechanism operatively connected with the former mechanisms, said feed-direction-changing mechanism including a hand-crank shaft mounted to rotate on an axis oblique to the axis of rotation of said stitch-forming and feeding mechanisms, means normally acting to apply a yielding resistance to the action of the feed-direction-changing mechanism, and means automatically operated, after the production of each group or succession of stitches of predetermined number, to interrupt the normal action of said yielding resistance means.

12. In a sewing machine, the combination of a rotary stitch-forming mechanism, a rotary feeding mechanism operatively connected with the latter, a feed-direction-changing mechanism operatively connected

with the former mechanisms, said feed-direction-changing mechanism including a hand-crank shaft and a hand-crank, the latter mounted to rotate on an axis oblique to the axis of rotation of said stitch-forming and feeding mechanisms, means normally acting to apply a resistance to the action of the feed-direction-changing mechanism, and means automatically operated, after the production of each group or succession of stitches of predetermined number, to interrupt the normal action of said resistance means.

13. In a sewing machine, the combination of a rotary stitch-forming mechanism, a rotary feeding mechanism operatively connected with the latter, a feed-direction-changing mechanism operatively connected with the former mechanisms, said feed-direction-changing mechanism including a hand-crank shaft mounted to rotate on an axis oblique to the axis of rotation of said stitch-forming and feeding mechanisms, including a grooved pulley and coacting brake-shoe, means normally acting to apply a resistance to the action of the feed-direction-changing mechanism, and means automatically operated, after the production of each group or succession of stitches of predetermined number, to interrupt the normal action of said resistance means.

In testimony whereof, I have signed my name to this specification, in the presence of two subscribing witnesses.

DONALD NOBLE.
